METHOD OF AND APPARATUS FOR TREATING THE INNER SURFACE OF TUBULAR BODIES WITH BLASTS

Wilhelm Eckler, Altona, Germany

Application August 31, 1933, Serial No. 687,675
In Germany October 30, 1931

12 Claims. (Cl. 51—14)

It is known to remove from the inner surface of tubular bodies, for instance iron tubes, the eventually adhering hammer-scale or the like, or to coat that surface with a certain substance 5 or composition, by subjecting it to the action of an appropriate blast which may be, for instance, a mixture of sand and compressed air or a liquid mixture or, perhaps, a liquid metal, the respective metal being projected or flung against the surface to be treated by means of a fluid under pressure, especially compressed air, as already mentioned. The respective blasting substance or mixture is conducted into the tubular body through a pipe located within that body and having 10 at its end an angular nozzle and being continuously rotated while the acting material is driven out through said nozzle against the surface to be treated, the tubular body being at the same time moved axially and care being taken 15 that the distance between the axes of that body and of said pipe remains unaltered.

My present improvements in that method and in the means for carrying it out consist therein that, firstly, the tubular body, the inner surface 25 of which is to be treated, is rotated besides being axially shifted, secondly, that body is given an inclined position while being moved in the two-fold manner mentioned, and that, thirdly, the inner supply pipe for the blast material is no 30 more rotated, but is and remains stationary. This arrangement and manner of operation constitute an important progress in the art. With the known apparatus the tubular body is in horizontal position. The pipe supplying the blast 35 material is provided with brushes contacting with the inner surface of the hollow body and removing from it the hammer-slag or the rust or the dirt that has, perhaps, adhered to said surface, as well as particles of the eventually used solid 40 blasting material, for instance sand grains, the respective particles being then further removed and carried away by means of a current of air. This is effected, however, not simultaneously with the blasting procedure, but thereafter, from time 45 to time, in that the means therefor are separate from the blasting means; they do not form a unit therewith.

Matters are otherwise with the present invention. It is important for the efficiency of the 50 method that the particles separated from the inner surface of the hollow body, and those employed for this purpose, are continuously, quickly and completely removed from the hollow body treated. This useful effect is obtained by the 55 rotary motion of that body and its oblique posi-

tion, as well as by making the inner supply tube stationary, so that the nozzle extends continually in one and the same direction.

An improved device for carrying out the improved method is shown diagrammatically and by 60 way of example on the accompanying drawing on which Figure 1 is partly (upper half) a vertical longitudinal section through, and partly (lower half) a side-view of, an apparatus designed according to this invention. Figure 2 is partly 65 (upper half) a transverse section through, and partly (lower half) an end-view of, said apparatus; and Figure 3 is a representation similar to Fig. 2, showing the blasting pipe (2) in an eccentric position relatively to the tubular body 70 or tube (1) just being treated.

In the example shown the hollow body is a comparatively long and comparatively narrow tube 1, and it is assumed that the inner surface of this tube is to be freed from adhering hammer-scale. 75 Normally centrally or axially in the tube 1 is located a pipe 2 for the supply of the blasting material or mixture, for instance sand grains and compressed air, this latter tearing then the sand with it and the mixture leaving the pipe 2 through 80 the oblique nozzle 3 which directs it against the inner surface of the tube 1. This tube is supported on rolls 6 and 6^a, of which the rolls 6 are affixed to a shaft 7 and the rolls 6^a are affixed to a shaft 7^a. The two shafts are supported in 85 bearings 8 secured to a plate 9 having downwardly extending lugs 11 from which extend forth pivots 14 bearing running rolls 10. These rolls run on rails (not shown) and these parts are arranged somewhat oblique, as appears from the acute 90 angle between the full line 13 and the dotted line 13'. This oblique arrangement is a particularly important feature of the invention.

The blast pipe 2 is provided with circular brushes which may be designed, for instance, 95 either as shown at 4 or at 4^a in Fig. 1. 4 is a cylindrical brush that is equipped at one side with a disk 8 consisting of a soft, yielding, elastic material, as for instance rubber and serving also for removing particles of hammer-scale etc. from the 100 inner surface of the tube 1. If the carriage 9 with all members, including the tube, is moved in the direction indicated by the arrow 12, quasi up-hill, the separated particles do not take part in this movement owing to the oblique position of the 105 tube and the rotary motion of the same. The separated particles are retained on the bottom of the tube by the brush and the flexible disk and arrive finally at the end of the tube, that is to say, the end of the obliquely upwardly moved tube 110

arrives finally where there are said particles, and when then the tube is withdrawn from the apparatus, the said particles can be removed, as will be clear without a further explanation.

5. The same result can be obtained with a multiple brush like 4^a in which the bristles of the two (or more) brush bodies are so arranged as to form screw-threads, as shown.

10. The brush 4, or 4^a, may be a plurality of the one or the other, serves at the same time for supporting the blasting pipe 2 in the tube 1. It is, however, not indispensably requisite that the pipe 2 is arranged centrally in the tube 1, as in Figs. 1 and 2; it may as well be arranged eccentrically, 15 as in Fig. 3, in which case the length of the bristles is, of course, correspondingly different. While with central arrangement of the pipe 2 there exists a certain tendency to turn or twist this tube owing to the rotary motion of the tube 1, that 20 tendency is practically zero when the tube 2 is located eccentrically, as in Fig. 3.

25. The brush 4 or 4^a may have rubber strips or the like instead of bristles proper, it being understood that said strips must be rigid enough to act in the required manner.

30. The shafts 7 and 7^a are rotated by an electro-motor (not shown) which may be used also for moving the carriage 9, 10, 11 for which purpose then, of course, suitable transmission means are provided. The motor may be located upon the table 9 of the carriage and connected with the source of current by a flexible cable.

35. Besides with the means for removing hammer-scale or the like from the inner surface of the tube, the apparatus may also be provided with means for removing undesired particles also from the outer surface of the same, the inner and the outer means operating then simultaneously so that the tubular body need be passed through the apparatus only one time in order to be cleaned at its inner, as well as at its outer side.

I claim:

1. The method of treating the inner surface of tubular bodies with blasts, consisting in giving the tubular body an inclined position, moving it lengthwise, rotating it at the same time, and subjecting it interiorly to the action of a stationary blast.

2. The method of treating the inner surface of tubular bodies with blasts, comprising giving the tubular body an oblique position, moving it axially, rotating it at the same time, and subjecting its inner surface to the action of a stationary blast directed in oblique position against the inner surface, substantially as set forth.

3. An apparatus for treating the inner surface of a tubular body with a blast, comprising, in combination, means for supporting the tubular body in an inclined position, means for moving it lengthwise, means for rotating it at the same time, and means for directing a stationary blast against the inner surface of the tube while it is being moved lengthwise and rotated.

4. An apparatus for treating the inner surface of tubular bodies with a blast, comprising, in combination, means for supporting the tubular body in an inclined position, means for mov-

ing it axially, means for turning it at the same time, a stationary blast pipe extending into the tubular body, and an angular blast nozzle at the free end of said pipe.

5. An apparatus for treating the inner surface of tubular bodies with a blast, comprising, in combination, means for supporting the tubular body in an inclined position; means for moving it lengthwise; means for rotating it at the same time; means for directing a stationary blast against the inner surface of the tubular body while it is being moved lengthwise and rotated, and means for removing from said surface the particles adhering to it. 80

6. An apparatus for treating the inner surface of tubular bodies with a blast, comprising, in combination, means for supporting the tubular body in an oblique position; means for moving it lengthwise; means for rotating it at the same time; a stationary blast pipe extending into the tubular body; an oblique blast nozzle at the free end of said pipe, and means attached to said pipe and adapted to remove from said inner surface the particles still adhering thereto. 85

7. An apparatus for treating the inner surface of tubular bodies with a blast, comprising, in combination, means for supporting the tubular body in an oblique position, moving it axially and rotating it at the same time; a stationary blast pipe extending into the tubular body; an angular nozzle at the free end of said pipe; a circular brush attached to this pipe and contacting at its circumferential surface with the inner surface of the said tubular body, said brush supporting the blast pipe in the said body. 90

8. An apparatus for treating the inner surface of tubular bodies with a blast, comprising, in combination, means for supporting the tubular body in an inclined position, moving it axially, and rotating it at the same time; a stationary blast pipe located within the tubular body; a blast nozzle at the free end of said pipe; two circular brushes attached to the blast pipe remote from one another, one of said brushes being located adjacent to the blast nozzle, substantially as set forth. 105

9. An apparatus as specified in claim 7, comprising, in combination with the circular brush, a yielding disk also located on the blast pipe and contacting at its circumference with the inner surface of the tubular body, for the purpose set forth. 110

10. An apparatus as specified in claim 7, comprising, in combination with the circular brush, a rubber disk also located on the blast pipe and contacting at its circumferential edge with the inner surface of the tubular body so as to wipe it, substantially as set forth. 115

11. An apparatus as specified in claim 6, in which the stationary blast pipe is arranged eccentrically in the tubular body. 120

12. An apparatus as specified in claim 7, in which the stationary blast pipe is arranged eccentrically in the tubular body and the circular brush is shaped accordingly. 125
